UNITED STATES PATENT OFFICE.

GEORGE A. SAVILLE, JR., AND PETER SCHMALL, OF LINCOLN, NEBRASKA, SAID
SCHMALL, ASSIGNOR TO SAID SAVILLE, JR.

OIL HEATER.

Application filed October 20, 1924. Serial No. 744,770.

To all whom it may concern:

Be it known that we, GEORGE A. SAVILLE, Jr., and PETER SCHMALL, citizens of the United States, residing at Lincoln, in the county of Lancaster and State of Nebraska, have invented certain new and useful Improvements in Oil Heaters, of which the following is a specification.

Our invention relates to oil heaters for warming and thereby thinning the oil in the crank case of an internal combustion engine.

The winter use of automobiles is materially restricted because of two factors; the freezing of the water in the radiator and the thickening of the oil in the crank case. Of the two, the latter is the more insidious because the driver of the automobile receives no warning until serious damage has been done to the bearings and other parts of the car. The circulation of the oil in most automobiles is maintained through a filter or screen, and when the oil becomes too thick to pass through the screen, it ceases entirely to circulate and to function as a lubricant.

The object of our invention is provision of a heating unit which receives the heat from the hot exhaust gases and transmits or applies the heat to the outer side of the crank case but in proximity to the screen. Other objects will be pointed out in the following description.

In the drawings,
35 Figure 1 is a view in perspective of our heating unit.

Figure 2 is a side elevation of an internal combustion engine with our oil heater attached thereto.

40 Figure 3 is a vertical sectional view of the strainer and the oil heater, showing particularly the relationship of each to the other and to the wall of the crank case.

The heating unit 10 is pan shaped, being closed on all sides but that which is in contact with the crank case. In the present instance it is shown as cylindrical in form, but it is to be understood that the size, form, and relative dimensions may be varied as required in the different installations. As shown in Figure 3 it is made to fit snugly against the outer side of the plate 11 which supports the oil strainer 12. It is formed with an inlet port and an exhaust port at

diametrically opposite points. The inlet port communicates with a nipple 13 which is secured to the wall of the heating unit around the inlet port. The outlet or exhaust port 14 is preferably left free as shown, but if for any reason it is desired to conduct the exhaust gases to some other point, then that port may also be provided with a nipple.

Inside the heating unit 10 there are two or more baffle plates 15 arranged transversely between the two ports. In order to fully utilize the heat of the exhaust gases, the baffle plates are staggered so as to conduct the exhaust gases through a tortuous path.

70 The heating unit 10 has a plurality of ears 16 secured thereto. The ears are formed from more or less resilient material which is bent into right angled form, and they are secured to the wall of the heating unit with their ear portions directed outwardly and lying in the plane of the open side of the heating unit. At their upper ends they are spaced somewhat from the edge of the heating unit. Each ear has an aperture for receiving one of the bolts 17 which secure the strainer plate to the wall of the crank case. Since the relative positions of the bolts 17 are not always uniform, it is necessary to allow for a little play in the ears, this being accomplished by the resilient character of the material from which the ears are formed and by slightly spacing the ears from the edge of the heating unit. There may be as many ears 16 as there are bolts 17, but our experience has been that the heating unit may be firmly secured by means of three equidistantly spaced ears as shown.

75 For utilizing a portion of the exhaust gases, the heating unit is connected at any desired point with the exhaust or exhaust pipe. Any suitable flexible tubing 18 is connected with the nipple 13 to communicate with an aperture in the exhaust or 100 exhaust pipe. To properly control the movement of the exhaust gas through the heating unit, we place a valve 19 anywhere in the connections whereby the flow of exhaust gas through the by pass may be 105 regulated or shut off entirely.

Our heating unit is positioned where it is convenient of access but where at the same

time it is entirely out of the way. When the valve 19 is opened, a portion of the exhaust gases rush through the by pass and through the heating unit. An intense heat is thus applied directly to the strainer plate at the very bottom of the strainer where the oil is thickest and where ice in the oil is most likely to accumulate and to clog the strainer. Since all parts of our oil heater 10 are positioned entirely outside the crank case and secured thereto by readily detachable securing means, the device may be removed in a few minutes' time and stored during the summer, but with the freezing 15 temperatures of winter it may be again attached without any difficulty and without the use of special tools. The fact that it is structurally entirely independent from the strainer is important. During the 20 warm season the presence of an oil heater is objectional because the accidental opening of the valve will result in the undue thinning and heating of the oil in the crank case. This cannot happen when, as in our 25 device, the heater can be so easily removed.

We are aware that other heaters have been designed for utilizing exhaust gases for heating the oil in the crank case, but so far as we are aware there is none that is 30 so readily attachable and detachable and which at the same time applies the heat directly to the outer surface of the strainer plate.

Having thus described our invention in 35 terms which will be readily understood by others skilled in the art to which it pertains, what we claim as new and desire to

secure by Letters Patent of the United States is:—

1. An oil heater having an inlet part and an outlet port, a plurality of baffle plates providing a tortuous passage between said inlet and outlet ports, said oil heater being adapted to be secured to the outer side of the crank case of an internal combustion 45 engine and in close proximity to the oil strainer, and a connection to said inlet port for receiving exhaust gases from the engine.

2. An oil heater having the form of the strainer plate of an internal combustion 50 engine and being adapted to be secured in intimate contact with the exterior surface of the strainer plate, said oil heater having an open side adjacent the strainer plate, an inlet port in the side of said oil heater, 55 a nipple secured to the said oil heater at the inlet port, a conductor connected to said nipple and adapted to be connected to receive exhaust gases from the engine and to conduct the exhaust gases into the said oil heater, baffle plates within said oil heater for providing a tortuous passageway for the exhaust gases within the oil heater, and resilient ears secured to the said oil heater, said ears being adjustable in position and being provided with apertures for receiving the bolts which secure the strainer plate to the wall of the crank case of the engine.

In testimony whereof we affix our signatures.

GEORGE A. SAVILLE, JR.
PETER SCHMALL.
